UNITED STATES PATENT OFFICE.

JEAN CHAVANNE, ETIENNE BRUYAS, AND JEAN PHILIBERT BALME, OF
ST. CHAMOND, LOIRE, FRANCE.

CENTRIFUGAL MACHINE FOR WASHING AND DRYING TEXTILES.

SPECIFICATION forming part of Letters Patent No. 305,049, dated September 16, 1884.

Application filed March 3, 1884. (No model.) Patented in France July 11, 1883, No. 156,479, and in England August 8, 1883, No. 3,861.

To all whom it may concern:

Be it known that we, JEAN CHAVANNE, ETIENNE BRUYAS, and JEAN PHILIBERT BALME, all citizens of the French Republic, and residents of St. Chamond, in the Department of Loire and French Republic, have invented certain new and useful Improvements in Centrifugal Machines for Washing and Drying Textiles, of which the following is a specification.

Our invention relates to machines in which textiles are washed and dried by centrifugal action; and the objects of our improvements are, first, to facilitate the regulating of the water-supply; and, second, to provide means for securing the sticks whereon the yarn-skeins are suspended during the work of the machine. We attain these objects by the mechanism illustrated in the accompanying drawings, in which—

Figure 1 is a side elevation of the machine, partly in section; and Fig. 2, a top view of one-half of the rotating drum, also partly in section.

Similar letters refer to similar parts throughout the several views.

A is the cylinder or jacket inclosing the drum or basket B, which is fastened to the vertical shaft *a*, rotated by friction-wheels *a'*. A perforated pipe, *b*, is arranged in the center of the basket. It incloses the shaft *a*, and rotates with the drum. Water enters into this pipe through the stationary funnel C in the direction of the arrow. At *m* the funnel is to be connected with a suitable pipe and cock. It is closed at the top and open toward the pipe *b*. A helicoidal strip, *d*, fastened around the shaft *a* and inside the pipe *b*, serves to distribute the water through the perfora-

tions of the pipe. Within the basket B are the 40 angle-shaped divisions G, forming sectional compartments S and cross-shaped compartments T around the axis of the rotating drum. The bars *i*, with the skeins M, are placed by pairs one above another, and are arranged to 45 form a square within the cross T in such a manner as to bear with their extremities against two adjacent divisions, G, and to place the skeins into the arms of the cross T. The centrifugal force of the rotating basket 50 causes the skeins to extend horizontally. The water, entering through the perforations of the pipe *b*, as required, washes the yarn and cleans every thread as they are separated from each other by the whirling motion. After 55 closing the water-supply, the water will be thrown by centrifugal force out from the skeins, which thus become perfectly dry.

Having thus fully described our invention, what we desire to claim and secure by Letters Patent is—

In machines for washing and drying textiles, the combination of the basket or drum B with the four angle-shaped divisions G, substantially as and for the purpose specified. 65

In testimony that we claim the foregoing as our invention we have signed our names, in presence of two witnesses, this 27th day of December, 1883.

JEAN CHAVANNE.
ETIENNE BRUYAS.
JEAN PHILIBERT BALME.
